United States Patent Office

Des. 222,318
Patented Oct. 12, 1971

222,318

TIRE

Hamilton Carter Jamison, 14202 Burtcliff,
Houston, Tex. 77037

Filed Feb. 6, 1970, Ser. No. 21,304

Term of patent 14 years

Int. Cl. D12—15
U.S. Cl. D90—20

FIG. 1 is an elevational view showing one side of a tire, according to the invention.

FIG. 2 is a front view of the tire shown in FIG. 1.

FIG. 3 is an elevational view showing the other side of the tire shown in FIG. 1.

The characteristic feature of a tire according to the invention is a flat design comprising plural V configurations circularly disposed on one sidewall of the tire.

I claim:

The ornamental design for a tire, as shown.
